ATTORNEY.

UNITED STATES PATENT OFFICE.

JOHN FINN, OF MILL VALLEY, CALIFORNIA.

DESIGN FOR AN AUTOMOBILE ARMREST.

Application filed May 9, 1927. Serial No. 21,886. Term of patent 14 years.

To all whom it may concern:

Be it known that I, JOHN FINN, a citizen of the United States of America, residing at Mill Valley, in the county of Marin and State of California, have invented a new, original, and ornamental Design for Automobile Armrests, of which the following is a specification, reference being had to the accompanying drawing, forming a part thereof.

I claim:

The ornamental design for an automobile armrest substantially as shown.

JOHN FINN.
